UNITED STATES PATENT OFFICE.

FEDOR E. BUSCH, OF CHICAGO, ILLINOIS.

SASH AND DOOR LOCK.

No. 822,505.

Specification of Letters Patent.

Patented June 5, 1906.

Application filed August 11, 1905. Serial No. 273 706.

To all whom it may concern:

Be it known that I, FEDOR E. BUSCH, a citizen of the United States, residing in the city of Chicago, county of Cook, and State of Illinois, have invented certain new and useful Improvements in Sash and Door Locks, of which the following is a full, clear, and exact specification.

This invention relates to improvements in sash and door locks composed of two members hinged together, one of which is permanently secured to the upper sash or to a door-frame and the other is adapted to be swung outwardly across the path of movement of the lower sash or the door, as may be, and either lock the sash against any movement whatever or limit the opening thereof and lock a door in a closed position, which swinging member is also adapted to be swung inwardly against the fixed member out of the path of movement of a sash or door.

The prime object of my invention is to have such a lock so constructed that when used in connection with a sash it will automatically assume a locking position when released from a position between the sash.

A further object of my invention is a sash-lock which when released from a closed position will not only automatically swing to a locking position, but which on assuming a locking position will be automatically locked against movement in any direction until unlocked by hand.

With these ends in view my invention consists in certain features and novelty in construction, combination, and arrangement of parts by which said objects and certain other objects hereinafter appearing are attained, all as fully described in reference to the accompanying drawings and more particularly pointed out in the claims.

In said drawings, Figure 1 illustrates a perspective view of a sash-lock embodying my invention, shown in its operative position in connection with a window sash and frame illustrated in detail; Fig. 2, a detached top plan view of a sash-lock embodying my invention; Fig. 3, a detail perspective of one of the members and particularly illustrating the lock-joint thereof; Fig. 4, a side elevation showing the locking member in its locking position, the dotted lines illustrating the unlocked position and the full lines the position assumed by the locking member when locked;

Fig. 5, a detail vertical section of a door and its frame, illustrating the position of the lock when the door is closed; Fig. 6, a side elevation of a modified form of sash-lock embracing my invention.

Similar figures of reference indicate the same parts in the several figures of the drawings.

7 indicates the fixed member of my sash and door lock, which, as shown in Fig. 1, is rigidly secured, by means of screws 8, to the side bar of an upper sash 9 of a window 10, which fixed member 7 is provided at one side, respectively, with upper and lower tubular lugs 11 and 12, forming bearings for a pin 13, which pin also passes through a tubular lug 14 on the movable or locking member 15, which is thereby hinged to the fixed member 17 on a vertical axis.

Coiled about the pin at a point between the lug 12 on the fixed member and the lower end of the lug 14 on the hinged member is a spring 16, projecting ends of which respectively bear against the fixed member 7 and the hinged or locking member 15 and in such relation thereto that when the swinging or locking member is forcibly swung from a position at a right angle to the fixed member, as shown in Figs. 1 and 2, toward a position parallel thereto the spring will be compressed and as a result automatically force the locking member to the position shown in said figures when it is released and maintain the locking member in that position until the resistance of the spring is overcome by force. In this connection it should be noted that owing to the usual guide-strip 17, employed between the upper sash 9 and the lower sash 18, the fastener when folded upon itself, as above described, sets so far in beyond the lower sash that when it is desirable to raise the window without locking it the lower sash will freely pass the upper sash, and vice versa.

When the locking member is in the position shown in Figs. 1 and 2—that is to say, at a right angle to the fixed member—it projects across the upper end of the lower sash, and if the lock is to be close down to the lower horizontal bar of the upper sash neither sash can move when the locking member is in that position; but my invention is particularly adapted to provide for partially opening one sash to the exclusion of the other or

In order to prevent the possibility of the swinging member actuating on the putty edge of the lower sash when releasing it from between the sash, the free end of the locking member 15 is preferably beveled at 19, so that, for example, in lowering the lower sash from a position above that for which the lock is set, the putty edge will ride downwardly on the incline without injuring the putty edge and until the sash is freed from the locking members, which by the action of its spring is forced to its locking position over the lower sash.

To prevent any possible manipulation of the locking member when in its locking position from the outside of the window—as, for example, by passing any instrument between the two sash, as may be when the one is slightly above the other, from the position shown in Fig. 1—the adjacent ends of the bearings 11 and 14, respectively, on the fixed member 7 and the locking member 15 are cut out, as shown in Fig. 3, forming opposing bearing-surfaces 20 and opposing stops 21, so arranged with reference to each other that the moment the locking member is swung to its locking position the stops 21, by the lifting action of the spring 16, lift the locking member 15, as indicated in Fig. 4, until the stops are in contact with each other, with the result that the locking member is positively locked against any substantial movement out of its locking position and will so remain until it is forcibly depressed until the opposing stops are out of contact, when it may be swung toward the fixed member if it is de-

sired to unlock the sash. On the other hand, 65
by the reverse operation—that is to say, when the sash-lock is released from between the two sash—it will automatically swing to and be locked in its operative position, or, in other words, the spring performs two functions, one of which is to automatically force the locking member to its operative position and the other is to lift, and thereby automatically lock it to the fixed member the instant it arrives at its locking position, the latter of which is due to the vertical force continuously exerted by the spring upwardly against the tubular bearing 14 of the locking member. In this connection it should be observed that a pin or projection on one member and a recess in the other will perform the same function, and therefore be the equivalent of cutting out the bearings, as above described. 70 75 80

In Fig. 6 is shown a modification of my invention, which consists in omitting the feature by which one member is locked to the other and in which there is added to the locking member a lower lug 14^a, between which and the lug 14 a spring is confined instead of as shown in Fig. 1, with the result that the vertical expansion and contraction of the same has no utility further than it will effect the tension exerted by its free ends bearing against both members. 95

In Fig. 5 I have shown the adaptation of my invention as and for a door-lock in which the fixed member 7 is secured to the vertical jamb 22 of the door 23, so that when the door is closed the locking member 15 will project across the inner face of the door, in which position the two members will be locked together and the door held in a closed position until the locking member is depressed and released from its stops. 105 100

Having described my invention, what I claim, and desire to secure by Letters Patent, is—

1. A sash-fastener comprising in combination a fixed member, a swinging member and a pivot connecting said members, a locking device opposing parts of which are upon adjacent portions of said members and a spring coiled about said pivot and provided with arms bearing against both of said members and constantly tending to move the swinging member toward and lift it into a locked position with the fixed member substantially as described. 110 115

2. A sash-fastener comprising in combination a fixed member provided toward its upper end with a locking part, a swinging member hinged thereto and provided with a locking part below but adapted to engage with said upper member, said swinging member being provided with a lower end bearing, whereby the swinging member is automatically secured in its locked position and against

accidental detachment by upward thrust or force substantially as described.

3. A sash-fastener comprising in combination a fixed member, a swinging member hinged to the fixed member said members having opposing bearing-surfaces and stops on adjacent portions thereof, and a spring lo-

cated on the hinged pin and adapted to raise one of said members so as to lock them in fixed position substantially as described.
